UNITED STATES PATENT OFFICE

ARTHUR M. TROGNER, OF EAST ORANGE, NEW JERSEY, ASSIGNOR TO WIRED RADIO, INC., OF NEW YORK, N. Y., A CORPORATION OF DELAWARE

REMOTE CONTROL RADIO RECEIVING SYSTEM

Application filed March 26, 1929. Serial No. 350,096.

My invention relates broadly to remote control radio receiving systems generally and more particularly to remote control of radio receivers where the frequency characteristics of the receiving set are adjusted at a position remote from the receiver.

One of the objects of my invention is to provide a remote control receiving system wherein a plurality of radio receivers may be individually adjusted from a remotely positioned control unit.

Another object of my invention is to provide a remote control receiving system in which a plurality of radio receivers are individually adjusted from a remotely positioned control unit and wherein the frequency adjustments of each receiver may be positively ascertained at such remote position.

Other and further objects of my invention are to provide a minimum of interconnecting wires between the radio receivers and the control unit and to provide a system which is easy to operate.

My invention will be more fully understood from the specification hereinafter following and by reference to the accompanying drawings, wherein:

Figure 1 is a schematic circuit diagram showing the remote control radio receiving system of my invention; and Fig. 2 is a simplified diagrammatic illustration of the remote control radio receiving system of my invention.

In my copending application Serial No. 345,854, is described a remote control radio receiving system similar in certain respects to the arrangement described and illustrated herein, the present arrangement possessing certain improvements and modifications not shown in my earlier application mentioned. It is oftentimes desirable if not necessary to place the radio receiving set at a considerable distance from the place where control of the receiver is desired. This is especially true where interference from other transmitters or from sources of industrial interference would not permit satisfactory reception otherwise. The remote control radio receiving system of my invention avoids many disadvantages inherent in other systems and

presents many advantages in simplicity and efficiency not experienced in systems of the type heretofore employed.

In Fig. 1 of the drawings two individual receiving sets are controlled by remote means. The two are designated as receivers "A" and "B". Receiver "A" comprises thermionic tubes 1, 2 and 3. The input circuit of thermionic tube 1 includes inductance 6 and capacity 8. Inductance 6 and capacity 8 are adjustably controlled by mechanical member 7.

Inductance 6 is inductively coupled with inductance 4a, the latter being connected to a space radio energy collecting system comprising antenna 4 and ground 5. An audio frequency oscillator 9 employs a thermionic tube having an input circuit comprising inductance 10 and capacity 12. Capacity 12 is adjustably controlled in common with the control of capacity 8, by mechanical member 7 actuated by motor 13. Motor 13 has a field winding 14. The connections of the armature and field windings are controlled by polarity reversing switch 25, 26, 27. A commutator 25 is actuated by a ratchet and pawl movement, the pawl actuated by armature 26 causing the movement of commutator 25 only on the forward stroke of the armature 26. The forward stroke of armature 26 is effected by the attraction of electromagnet 27. Oscillator 9 is coupled to transmission line 17 by capacity 16. A polarized relay comprising electromagnet 30, armature 31 and contact members 32, 33 controls the energization of electromagnet 27 of the polarity reversing switch. Audio frequency energy is excluded from electromagnet 30 by means of audio frequency choke coil 15. Time delay relay 36 opens and closes the energization circuit of oscillator 9 and may provide for deenergizing the oscillator a predetermined time after the last tuning operation.

The arrangement of receiver "B" is similar to that of receiver "A." Space radio collecting system 4b, 4c and 5 is inductively coupled with inductance 6a included in the input circuit of thermionic tube 1a. Thermionic tubes 2a and 3a are coupled with the amplifier

circuit arrangements. The frequency characteristics of oscillator 9a are controlled in common with the adjustment of capacity 8a and inductance 6a by a common mechanical member 7a. The frequency range of oscillator 9a should be entirely different from the range of oscillator 9, and there should not be even any close harmonic relationship between the two.

Member 7a is actuated by motor 13a. Motor 13a has a field winding 14a connected with polarity reversing switch 25a, 26a, 27a. The generated audio frequency energy of oscillator 9a is transmitted to line 17 by means of capacity 16a connected with inductance 10a. The energization of oscillator 9a is controlled by time delay relay 36a. Energization of electromagnet 27a of the polarity reversing switch is controlled by polarized relay 30, 31, 32, 33, the contact 32 connecting with armature 31.

Transmission wires 17, 17a and 17b are connected with receivers "A" and "B" and to the distant control unit. The circuit for controlling the frequency characteristics of the unit comprising thermionic tube 1, and oscillator 9, and the unit comprising thermionic tube 1a and oscillator 9a includes line wire 17 and a common ground circuit 5. Line wires 17a and 17b carry the signaling energy from receivers "A" and "B" respectively. The distant control unit comprises reproducing means 23 and 23a, audio frequency indicating meters 21 and 21a, condensers 22 and 22a, polarity reversing switch 20, source of energy 19 and audio frequency choke coil 18. With both receivers A and B in operation, the received signaling energy is reproduced in reproducers 23 and 23a respectively. The generated signaling energy of oscillators 9 and 9a is transmitted over line wire 17. At the distant control unit, audio frequency meter 21 indicates the frequency adjustment of receiver "A," since the frequency characteristics of oscillator 9 are controlled in common with adjustments in the frequency characteristics of the input circuit of thermionic tube 1.

In like manner meter 21a indicates the frequency adjustment of receiver "B" in terms of the frequency adjustment of oscillator 9a. Condensers 22 and 22a prevent direct current from reaching the meters 21 and 21a, permitting however low frequency impulses to pass. Polarity reversing switch 20 is adapted to apply potential source 19 between line wire 17 and ground 5 with either polarity.

Figure 2 shows a simplified diagrammatic illustration of the remote control radio receiving system of my invention. Reference characters shown in Fig. 2 correspond to those employed in Fig. 1. Signal energy transmission wires 17a and 17b are not shown in this illustration. Receiver "A" and re-

ceiver "B" having frequency adjusting elements 8 and 8a respectively are adjusted by the operation of motors 13 and 13a respectively. The frequency characteristics of oscillators 9 and 9a are controlled by frequency adjusting elements 12 and 12a cooperatively actuated with elements 8 and 8a respectively. The generated audio frequency energy of oscillators 9 and 9a is transmitted to line wire 17 by means of coupling condensers 16 and 16a respectively. Polarized relay 30, 31, 32, and 33 controls the energization of electromagnetic reversing switch 25, 26, 27, or of switch 25a, 26a, 27a, depending on the position of armature 31, and whether contact is made with member 33 or 32. This selectivity is controlled by the polarity of the source energizing electromagnet 30. Reversing switches 25, 26, 27, and 25a, 26a and 27a are adapted to reverse the connections of the armature and field windings of the motors connected with the respective switches, the pawls actuated by arms 26 and 26a moving commutators 25 and 25a respectively always in the same direction.

Alternate segments of commutators are interconnected to effect the desired reversal of connections. Time limit or time delay switches 36 and 36a are adapted to energize and deenergize oscillators 9 and 9a and to de-energize the oscillators a predetermined time after the last tuning operation. Audio frequency choke coil 15 prevents the generated energy from oscillators 9 and 9a from reaching the relays and reversing mechanism. Transmission wire 17 leads to the remote control unit. The generated audio frequency energy from oscillators 9 and 9a passes the condensers 22 and 22a, actuating audio frequency indicating meters 21 and 21a respectively. Audio frequency choke coil 18 prevents the audio frequency energy from reaching switch 20a and sources 19, 19a. Switch 20a as here shown is a single-pole, double-throw switch while that shown in Fig. 1 is of the double-pole, double-throw design. Sources 19 and 19a are adapted to control the energization of polarized relay 30, 31, 32, 33, armature 31 contacting with member 32 or with member 33 according as switch 20a connects source 19 or source 19a with the line 17. Armature 31 returns to neutral position when switch 20a is in the neutral position. The reversing switches 25, 26, 27 and 25a, 26a, 27a are selectively energized depending upon the position of switch 20a at the remote control unit. In operation, switch 20a is moved, let us say to connect source 19a to line 17 and ground 5. Electromagnet 30 is energized and armature 31 contacts with member 32. This energizes electromagnet 27a and energy is supplied to motor 13a. The commutator 25a is moved a sufficient amount to reverse the connections of motor 13a from their previous condition thereby causing the direction 130

of rotation of motor 13a to be the reverse of its previous operation.

This direction of rotation may at this time be such as to cause a progressive increase in the frequency adjustment of element 8a. A similar change in the adjustment of member 12a is likewise effected. Because of time limit relay 36a being energized simultaneously with the energization of relay 30, 31, 32, 33, the audio frequency oscillator 9a is energized. The generated energy from oscillator 9a is transmitted to line 17 and to the remote control unit where frequency meter 21a indicates the progressive increase of frequency. If switch 20a is now opened, electromagnet 30 is deenergized which indirectly causes motor 13a to stop. Relay 36a is also deenergized thereby deenergizing oscillator 9a. If source 19a is again connected with line 17 by switch 20a, the operation of polarized relay 30, 31, 32, 33 is the same as is also reversing switch 25a, 26a, 27a. Commutator 25a reverses the connection of the windings of motor 13a and hence causes the direction of the motor's operation to be reversed. This would cause a decrease in the frequency characteristics of element 8a, and also of element 12a, and the progressive decrease would be indicated on meter 21a. The operation of receiver "A" is similar to the operation of receiver "B" just referred to. Switch 20a is moved to the opposite contacting position with source 19 thereby causing a reversal of the polarity of the source energizing electromagnet 30. This causes the energization of motor 13 and the actuation of reversing switch 25, 26, 27.

Progressive adjustment of elements 8 and 12 is indicated by meter 21 at the distant control unit. Reversal of the adjustment either increasing or decreasing the frequency characteristics is accomplished by opening the switch 20a and again closing the same to make connection with source 19. The progressive change in the frequency adjustment is indicated by meter 21.

Many modifications of my invention are possible. Receiving sets with any number of controls may be adjusted, the receiving sets having any desired circuit arrangements other than those shown in the drawings. Any number of receiving sets may be controlled in a manner similar to that described herein, each of the receivers being provided with an audio frequency oscillator having a frequency range differing each from the other. The frequency range of the oscillator circuits should be widely different. Telephone receivers are illustrated, however, it is obvious that loud speakers either with or without amplifiers may be employed. The polarity reversing switch indicated at 25, 26 and 27 may be of a design other than that illustrated.

I realize that many modifications of my in-

vention are possible without departing from the spirit of my invention and it is to be understood that the embodiments of my invention shall not be restricted by the foregoing specification or by the accompanying drawings but only by the scope of the appended claims.

What I claim as new and desire to secure by Letters Patent of the United States is as follows:

1. A remote control radio receiving system comprising in combination a plurality of radio receivers having individual frequency adjusting means actuated by individual electric motors, individual audio frequency oscillators having frequency adjusting means actuated in common with the frequency adjusting means of said receivers respectively, a remote control unit adapted to selectively energize said motors, individual frequency indicating means at said remote control unit and a single control circuit extending between said receivers and said control unit and carrying control currents and audio frequency currents whereby the adjustments of said receivers may be ascertained in terms of the frequency adjustments of said oscillators.

2. In a remote control radio receiving system, a pair of radio receiving sets, individual tuning controls for each of said sets, a pair of audio frequency oscillators of different frequency ranges, frequency varying means for each of said oscillators, individual means for actuating the frequency varying means of each of said oscillators cooperatively with the tuning controls of said receiving sets respectively, a separate reversible motor for driving each of said individual means, an electromagnetic reversing switch for each of said motors adapted to reverse the polarity of the potential applied to said motor with each impulse applied to its control winding, a polarized relay having contacts connected to each of said switches respectively, a remote control station for said receiving sets comprising a switch, a source of control potential, a pair of frequency meters respectively adapted to cover the frequency ranges of said audio frequency oscillators, and a single common control circuit connecting said remote control station to said receiving sets and oscillators, whereby each of said receiving sets may be selectively tuned from said control station, and the tuning of each of said receiving sets is positively indicated at said control station.

3. In a remote control radio receiving system, a pair of radio receiving sets, individual tuning controls for each of said sets, a pair of audio frequency oscillators of different frequency ranges, frequency varying means for each of said oscillators, individual means for actuating the frequency varying means of each of said oscillators cooperatively with the tuning controls of said receiving sets respectively, a separate reversible motor for

- driving each of said individual means, an electromagnetic reversing switch for each of said motors adapted to reverse the polarity of the potential applied to said motor with each impulse applied to its control winding, a polarized relay having contacts connected to each of said switches respectively, a remote control station for said receiving sets comprising a switch, a source of control potential, a pair of frequency meters respectively adapted to cover the frequency ranges of said audio frequency oscillators, and a single common control circuit connecting said remote control station to said receiving sets and oscillators, individual circuit elements connected for electrically isolating said motors from said oscillators, individual circuit elements connected for electrically isolating said frequency meters from said source of control potential and said switch, whereby each of said receiving sets may be selectively tuned from said control station, and the tuning of each of said receiving sets is positively indicated at said control station.
4. In a remote control radio receiving system, a translating station, a control station, said translating station comprising two tuning controls to be selectively actuated, a pair of audio frequency oscillators of different frequency ranges, frequency varying means for each of said oscillators, individual means for actuating the frequency varying means of each of said oscillators cooperatively with each of said tuning controls respectively, a separate reversible motor for driving each of said individual means, means for reversing the direction of rotation of each of said motors, a polarized relay having its contacts connected for selectively actuating each of said reversing means, said control station comprising a switch, a source of control potential, and a pair of frequency meters of ranges corresponding respectively to each of said oscillators, and a single common control circuit between said translating station and said control station, whereby each of said receiving sets may be selectively tuned from said control station, and the tuning of each of said receiving sets is positively indicated at said control station.
5. In a remote control radio receiving system, a translating station, a control station, said translating station comprising two tuning controls to be selectively actuated, a pair of audio frequency oscillators of different frequency ranges, frequency varying means for each of said oscillators, individual means for actuating the frequency varying means of each of said oscillators cooperatively with each of said tuning controls respectively, a separate reversible motor for driving each of said individual means, means for reversing the direction of rotation of each of said motors, a polarized relay having its contacts connected for selectively actuating each of said reversing means, said control station comprising a switch, a source of control potential, and a pair of frequency meters of ranges corresponding respectively to each of said oscillators, and a single common control circuit between said translating station and said control station, whereby each of said receiving sets may be selectively tuned from said control station, and the tuning of each of said receiving sets is positively indicated at said control station.

ARTHUR M. TROGNER.
